United States Patent Office.

LANDON LIMERICK AND A. H. E. STEIN, OF LOUISVILLE, KENTUCKY, ASSIGNEES TO
JAMES T. HAIR AND O. W. RICHARDSON.

Letters Patent No. 91,645, dated June 22, 1869.

ADVERTISING-ATTACHMENT TO TABLES, &c.

The Schedule referred to in these Letters Patent and making part of the same.

To whom it may concern:

Be it known that we, LANDON LIMERICK and A. H. E. STEIN, both of Louisville, Jefferson county, Kentucky, have invented a new and useful Advertising-Attachment to Tables, &c.; and we do hereby declare the following to be a full, clear, and exact description thereof, reference being had to the accompanying drawings, making part of this specification.

Our invention relates to an advertising-medium, consisting of a suitable frame for the reception of business-cards, said frame being arranged so as to revolve around a shaft, which is secured to a table, desk, or other fixed object.

This mechanical device we call a "rotary advertiser."

The accompanying drawing is a perspective view of a rotary advertiser embodying our improvements, one of the cards being represented as partially removed, so as to show the grooves or clips by which the slides and cards are secured within the revolving frame.

A represents a table, which is supported upon feet B B'; and rising vertically from the centre of this table is a fixed shaft, C, to which is connected, by arms D D', and a collar, d, the revolving frame E, which is adapted to receive a number of business-cards of different sizes and dimensions.

This frame may be constructed of any suitable material, either wood or metal, and it is furnished with clips F, for the reception of the glass slides G, and also of the business-cards.

This provision of the clips F permits of the ready removal of the glass slides, for the purpose of cleaning, &c., and it also enables the cards to be withdrawn at any time and be replaced by others.

Where it is desired to retain the cards, they may be permanently secured to the slides, or their subject-matter may be permanently painted on the slides without the use of cards.

The device may thus be made highly ornamental and attractive, and its effect may be still further enhanced by a light placed within the revolving frame.

The slides serve as a glazing to the cards, greatly enriching their appearance, and also protecting them from dust.

We claim herein as new, and of our invention—

The combination of a table, A B B', fixed shaft C, and revolving frame E D D', the latter being provided with grooves or clips F, for the reception of the transparent slides G, and also of the business-cards, in the manner described and represented.

In testimony of which invention, we hereunto set our hands.

LANDON LIMERICK.
A. H. E. STEIN.
